UNITED STATES PATENT OFFICE

2,324,216

TOBACCO PIPE

Kurt F. J. Kirsten, Seattle, Wash.

Application May 6, 1940, Serial No. 333,475

2 Claims. (Cl. 251—95)

This invention relates to tobacco pipes and is a continuation-in-part of my parent application for Letters Patent of the United States filed August 30, 1938, Ser. No. 227,483, said pipe, describing the same in more particularity, being one in which the tobacco-receiving bowl is mounted on a metallic barrel, the barrel having a through-bore into which the products of combustion are fed from the bowl. A plug-valve and the usual mouth-piece serve as closure elements for the two ends of the bore. In addition to this closing function, the plug-valve by rotary movement in the bore serves the added office of sealing the barrel against passage of moisture therefrom into the tobacco bowl. It will be understood by reason, principally, of the metallic nature of the barrel that there is an appreciable deposit of coal tars and the like from the smoke, the metal promoting the condensation processes, and that the closure elements must therefore be frequently removed for cleaning the barrel. Stating the same generally, the objects of the invention are to so engineer a pipe of the character described that the closure elements, namely the plug-valve and the mouth-piece, may be readily removed from their respective seat and wherein each of these closure parts, when applied to the barrel, is assured a leakproof fit relative to the seat.

Further and more particular objects and advantages of the invention will appear in the course of the following description and claims, the invention consisting in the novel construction and in the adaptation and combination of parts hereinafter described and claimed.

In the drawing:

Figure 1 is a fragmentary longitudinal vertical section representing, appreciably enlarged from a true scale, a pipe assembly of barrel, bowl and plug-valve embodying the present improvements.

Fig. 2 is a transverse vertical section on line 2—2 of Fig. 1; and

Fig. 3 is a diagrammatic view indicating salient angularities which characterize the plug-valve and its seat, there being considerable discrepancy between the indicated and the executed angles in order thereby to clarify the illustration.

The barrel of the pipe is denoted by the numeral 5 and is or may be of Duralumin or other light-weight metal relatively high in heat conductivity having a throughbore 6 which is cylindrical excepting for the two ends which are flared. In the upper wall of the barrel proximate to but spaced rearwardly from the forward flare is a port 7 by which smoke is drawn into the bore

from a tobacco-receiving bowl 8, the attachment of this bowl being desirably accomplished by prolonging the port upwardly through an up-standing and internally-threaded neck 9 over which the bowl seats, and threading into the neck a headed center-bored metallic screw 10 which finds bearing engagement against the floor of the bowl. Into the rear end of the bore is fitted a removable mouth-piece (not shown) and in the forward end is fitted a removable plug-valve 11. The present invention relates primarily to the plug-valve and its seat but it will be obvious that some of the details of construction of the plug-valve and its seat are as well applicable to the mouth-piece and its seat, and to the extent of this applicability my intention is to include one by reference to the other.

Referring therefore to the plug-valve, and describing first the seat therefor, it will be seen from an inspection of Fig. 3 that the flare which characterizes the forward end of the bore is produced to an angularity of 5° from the axial line of the bore, and that there is provided between this end flare and the cylindrical bore proper of the barrel a 3° flare.

The plug itself is desirably metallic and is in the nature of a thimble having a knurled head 12 and a tubular neck 13. The neck, considering its external surface, is produced at the two ends, which is to say proximate to and remote from the head, with cylindrical parts 14 and 15 and between the cylindrical parts has a tapering part 16 which is arranged to seat against and therefore generally corresponds in angularity and length to the end flare of the barrel. Said cylindrical part 14 is formed to a diameter somewhat reduced from the diameter which obtains at the outer limit of the end flare, and the cylindrical part 15, being the part remote from the head, closely fits the body proper of the bore and in the seated position of the plug projects into the bore beyond the rear limit of the smoke port 7. 17 denotes a port provided in the wall of the plug in a position whereat, by rotation of the plug, the port is brought into and out of register with the port 7, and it will be noted that such port 17 is of a sufficient diameter and so located in relation to the center-bore of the screw 10 as to permit the plug to wear-in to a degree commensurable with the cylindrical part 14 without interrupting a free travel of the smoke into the barrel. Otherwise stated, the port 17 and the center-bore of the screw 10 are so related, one to the other and to the length of the cylindrical part 14, as to maintain throughout the life of the

valve an uninterrupted flow of smoke from the feed conduit into the barrel.

While the 3° flare of the barrel wall functions in effect to round the shoulder which would otherwise occur at the point of juncture between the cylindrical and the 5° surfaces, this important end may be augmented or, in point of fact, an equivalent end accomplished by grooving the plug circumferentially at the point of juncture of the cylindrical and tapering parts 15 and 16, respectively, affording thereby what may be considered a reverse fillet 18. While the delineating edges of this groove are barely discernible in actual practice the showing is exaggerated in the drawing to differentiate the groove from the adjoining surfaces.

Generalizing somewhat, I have found that a proper seating depends primarily upon the elimination of wear in a spot sense, as distinguished from a wearing action distributed over an extended area. This I have accomplished by deleting abrupt shoulders between adjoining faces. Such removal of the shouldering edges is also of very major import in that it holds a pocket of air between the plug and its seat to prevent the plug from becoming "frozen" in the barrel. The flare of the seat, which is to say the 5° angle, I consider relatively critical to the operating efficiency of the plug.

What I claim is:

1. In a smoking device, in combination: a barrel member formed with a smoke chamber therein and having a bore leading to said chamber and functioning as a seat for the reception of a removable plug-valve, said bore being substantially cylindrical at its inner end and having a tapered part at its outer end and, in the wall of said cylindrical part, providing a port for the admission of smoke to the chamber of the barrel; and a removable plug-valve arranged to seat in said bore, having its inner and outer parts pro-

duced to angularities corresponding with the inner cylindrical and the outer tapered parts of the seat and, between said inner cylindrical and outer tapered parts, being circumferentially grooved to provide a reverse fillet functioning in the seated position of the valve to lap the point describing a meeting of the plane of the inner cylindrical part of the bore with the plane of the outer tapered part of the bore, said inner cylindrical part providing means acting by rotation of the seated valve to open and close the smoke port in relation to the chamber.

5 2. In a smoking device, in combination: a barrel member formed with a smoke chamber therein and having a bore leading to said chamber and functioning as a seat for the reception of a removable plug-valve, said bore being substantially cylindrical at its inner end, having a tapered part at its outer end and, between and merging with said inner and outer cylindrical and tapered parts, being provided with a central tapered part of an angularity less than that of the outer taper, the wall of said cylindrical part being ported for the admission of smoke to the chamber of the barrel; and a removable plug-valve arranged to seat in said bore, having its inner and outer parts produced to relative angularities corresponding with that of the inner cylindrical and the outer tapered parts of the seat and characterized as to length in that, when seated within the bore, the tapered surface of the valve extends inwardly beyond the point of juncture of the outer taper with the central taper of the bore, and the cylindrical surface of the valve extends in the opposite direction beyond the point of juncture of said central tapered part with the inner cylindrical part of the bore, said cylindrical part of the valve having means acting by rotation of the seated valve to open and close the smoke port in relation to the chamber.

KURT F. J. KIRSTEN.
